UNITED STATES PATENT OFFICE.

LOUIS G. KORTRIGHT, OF CUMBERLAND, MARYLAND, ASSIGNOR TO THE POTOMAC GLASS COMPANY, OF CUMBERLAND, MARYLAND, A CORPORATION OF MARYLAND.

DESIGN FOR A GLASS VESSEL OR SIMILAR ARTICLE.

49,744.

Specification for Design.

Patented Oct. 10, 1916.

Application filed June 6, 1916. Serial No. 102,100. Term of patent 7 years.

To all whom it may concern:

Be it known that I, LOUIS G. KORTRIGHT, a citizen of the United States, and residing at Cumberland, in the county of Allegany and State of Maryland, have invented a certain new, original, and ornamental Design Applied to a Glass Vessel or Similar Article, of which the following is a specification, reference being had to the accompanying drawing, forming a part thereof, wherein a superficially ornamented vessel is shown in elevation.

The design is repeated around the article, the lower portion of the spray which dis-

pears in the right hand margin of the view being a duplicate of the stem portion which is shown at the left hand margin.

The design is shown applied to a goblet of conventional form, the shape of which is not claimed.

I claim:

The ornamental design applied to a glass vessel or similar article, substantially as shown and described.

LOUIS G. KORTRIGHT.
